UNITED STATES PATENT OFFICE.

SAMUEL D. PAGE, OF DES MOINES, IOWA.

DESIGN FOR A PAD-RACK.

55,077.

Specification for Design.

Patented May 4, 1920.

Application filed February 12, 1918. Serial No. 216,823. Term of patent 14 years.

To all whom it may concern:

Be it known that I, SAMUEL D. PAGE, a citizen of the United States, and resident of Des Moines, in the county of Polk and State of Iowa, have invented a new, original, and ornamental Design for a Pad-Rack, of which the following is a specification, reference being had to the accompanying drawing, forming part thereof.

Figure 1 shows a front elevation of a pad rack illustrating my new design, and

Fig. 2 shows a side elevation of the same.
I claim:

The ornamental design for a pad rack, as shown.

Des Moines, Iowa, January 9, 1918.

SAMUEL D. PAGE.
